CLEANER SILENCER STRUCTURE

James D. Karn, Flint, John D. McMichael, Swartz Creek, and Wesley W. McMullen, Flint, Mich., assignors to General Motors Corporation, Detroit, Mich., a corporation of Delaware

Application September 27, 1954, Serial No. 458,306

8 Claims. (Cl. 183—44)

This invention relates to air cleaner and silencer units for use with engines and other devices having air induction means and more particularly to a unitary cleaner and silencer structure for automotive and other uses.

Air cleaners and silencers are generally made up as separate elements which are later coupled together to form a cleaner silencer assembly. It has been found, however, that in assembling such extraneous factors are introduced which may adversely affect the attenuation of sounds within the silencer. Such factors include the coupling of the separate elements and the necessity of an adequate acoustical seal therebetween.

It has been found that the most efficient cleaner silencer assembly is a unitary construction wherein necessary acoustical impedance, capacitance, and other factors may be designed into the silencer with direct relation to a specific cleaner. It is further found that a cooperative relation of walls and surfaces between elements may be provided which presents great savings in materials, in space, and in man-hours otherwise necessary in the assembly and adjustment of separate elements.

It is now proposed to provide an air cleaner silencer structure similar to that of copending application S. N. 392,338 entitled Cleaner Silencer Unit and filed November 16, 1953, in the name of Wesley W. McMullen. The proposed cleaner silencer is inexpensive to make in that a relatively small number of parts are used, most of which are sheet metal stampings. It is proposed to provide a unitary cleaner silencer arrangement which occupies a limited amount of space and which includes adequate internal chamber space to provide for an acoustic capacitance arrangement eliminating annoying high frequency noises. It is further proposed to provide adequate acoustical impedance means within the limited space available to attain sufficient sound attenuation.

In the drawings:

Figure 1 is a cross-sectional side elevational view of a unitary cleaner silencer structure embracing the principles of the invention taken in the plane of line 1—1 of Figure 2 looking in the direction of the arrows thereon.

Figure 2 is an upper plane view of the proposed cleaner silencer with parts broken away to better illustrate the internal structure thereof.

The cleaner silencer structure 10 includes an assembly of stamping arranged to provide a cleaner element 12 and a silencer element 13.

The cleaner element 12 comprises a casing 14 having a continuous side wall 16 and a bottom wall 17. The bottom wall 17 is formed to provide a closed upwardly extending or cupped central part 18 surrounded by a downwardly extending annular part 19. The space within the casing 14 is adapted to be filled entirely with filtering material 21 of any suitable type, the filtering material being adapted to extend entirely across the chamber formed by the casing 14 from within the side wall 16 and to entirely cover the bottom wall 17. In the present instance, the filter element 21 of filtering ma-

2

terial has been pressed or molded to substantially fit the shape of the interior of the casing 14.

The annular part 19 of the wall 17 is adapted to be radially and circumferentially slotted in such manner that 5 spacing members 22 may be bent downwardly from the annular part 19 to provide spaced and annularly disposed inlet openings such as that indicated at 23. The openings 23 provide the only air inlet means extending through the casing 14 for the admission of air to be cleaned by 10 the filter element 21. Surrounding the lower part of the casing 14 is an inlet casing 24 which is formed by a continuous side wall 26 and a closed bottom wall 27. The side wall 26 may be uniformly spaced from the side wall 16 to provide an annular inlet passage 28 leading to the lower part of the cleaner casing 16 and to the inlet opening means 23. The lower wall 27 has an outwardly depressed annular part 29 and an upwardly and inwardly depressed central part 31. The part 31 is adapted to extend within but in spaced relation to the part 18 of the wall 17 of the cleaner casing 14. The outwardly depressed part 29 of the inlet casing 27 is spaced below the lower extremity of the spacing means or supports 22 and provides an oil chamber or sump indicated at 32. The oil chamber or sump 32 is adapted to be filled with oil during the operation of the device to the level indicated at 33.

The central part 31 of casing 24 extends upwardly within the wall 17 to a height exceeding the oil level 33.

Between the lower walls 17 and 27 is an oil control 30 baffle 34 for the cleaner 12. The baffle 34 may be formed to provide an upwardly depressed part 36 which may fit the exterior surface of the upwardly depressed part 18 of the wall 17. Beneath the inlet openings 23 the outer part of the baffle 34 slopes downwardly towards the wall 26. The supports 22 are adapted to engage and to rest upon baffle 34. The wall 26 is formed to include an annular bead or rib 37 engaged by the baffle 34 for supporting the baffle and for compressing the baffle against supports 22 and the outer surface of wall 18 against wall 40. Openings 35 are struck from baffle 34 about and near the peripheral edge thereof to provide passage means through which the oil may circulate from the under to the upper side of the baffle during operation of the cleaner. Apertures 40 are also formed in baffle 34 directly beneath the inner edge of openings 23 to enable the return flow of oil from filter 21 to pass under the baffle where foreign material which may have been washed back with the oil may be collected in sump 32. The inlet casing 26 may be held in position around the cleaner casing 14 by fastening means such as the bolt and wing nut device indicated at 38. The head of the bolt may engage the inner surface of the wall 16 and the bolt may extend through and be staked within aligned openings in the walls 17 and 27 and the baffle 34 so that when the 50 wing nut is tightened the casings 14 and 24 will be drawn together and in so doing will compress the outer annular portion of baffle 34 into rattle free engagement with wall 26 and spacers or supports 22, and the inverted cupped portion 36 of the baffle into sealing engagement with the outer surface of part 18 of bottom wall 17 of the cleaner 55 element.

It will be apparent that when the wing nut is removed the inlet casing 24 may be entirely removed from the casing 14 and the baffle 34 so that the casing may be cleaned and new oil may be supplied to fill the sump 32.

The upper wall 39 of the cleaner 12, which is a common wall separating the cleaner and silencer elements 12 and 13 respectively, may be generally arcuate in 60 formation to provide an outlet chamber 41 about the filter element 21 and the casing 14. The space above wall 39 is enclosed by an inverted cupped annular wall indicated at 42 and a conical joining wall 45 which are

crimped together as at 46. The adjacently engaged edges of walls 16, 39 and 45 are flanged as at 43 to provide means for securing the walls together. Between the peripheral flanges on the walls 39 and 16 it may be considered desirable to provide a screen 44 which extends over the filter element 31 for securing the filter element within the casing 14.

The wall 39 is formed upwardly within the space within wall 42 to enlarge chamber 41 and to accommodate a tube or conduit 49 disposed obliquely within silencer 13. The tube 49 extends through an outlet opening formed in wall 39 to provide an outlet passageway from chamber 41 above the cleaning element 21. A flange 48 secured to the tube 49 provides means for securing the tube within the outlet opening of wall 39. The tube 49 extends from well within chamber 41 into the cover 51 of the silencer element and has the outlet end thereof disposed within the cover. A tubular extension member 47 flared at its inner end as at 55 is telescoped within the inlet end of tube 49 to increase the length of the outlet passage within chamber 41. Apertures 65 may be formed within the wall of tube 49 at any position along its length to provide acoustical passages communicating with the chamber 66.

The upper end of the silencer 13 may be formed by a closure, cap or end casing indicated at 51. The end casing 51 may be formed by an upper wall 52 and a lower wall 53, the upper wall being formed to provide a continuous side wall 54 extending laterally toward the lower wall 53. A flange 56 is provided around the peripheral edge of the lower wall 53 which is received within a bead 57 formed in wall 52 for securing the two walls rigidly together.

The end casing 51 may be elongated in formation as is shown by Figures 1 and 2 and may be provided adjacent one end thereof with a relatively large opening surrounded by a flange 58 formed in the lower wall 53. The flange 58 is adapted to be disposed in telescopic relation to the upper end of the wall 42 so that the two may be rigidly and permanently secured together to close the upper end of the silencer chamber. With such construction it will be apparent that the end casing 51 has a part extending laterally from the upper end of the structure to provide an elongated and relatively wide outlet which may be connected to the induction system of an engine or any other device.

The end of the casing 51 opposite the flange 58 may be flanged as indicated at 59 to form an outlet passage 60 and may be slotted around the flange 59 as indicated at 61 to provide means for connecting the structure to the induction passage of any device with which the structure may be used. Attaching means such as that indicated at 62 may extend around the flange 59 for tightening the flange around the induction means.

The silencer 13 also may be provided with sound absorbing means 71 which may be secured against the inside surface of an obliquely disposed part 72 of the side wall 54 of the casing 51 and immediately adjacent the outlet passage 60 leading from the structure. The slope of the wall part 72 is made in such a way as to direct the air flowing through the structure downwardly into the outlet passage 60. The sound absorbing means 71 may be constructed in any suitable manner as by providing a fibrous body of sound absorbing material 74 within a perforated wall 76 extending across the end of the casing 54. The wall 76 may be provided with flanged ends 77 which may be welded or otherwise secured to the wall 52. The sound absorbing material 74 may be employed to absorb high pitch, hissing sounds that may emanate from the induction means through the outlet opening passage 60.

It will be apparent that the structure 10 is largely formed from a relatively small number of parts secured together in such a way as to constitute a single unit. The only parts which require removal in order to service the structure is the casing 24.

A unique structural arrangement is provided in this integral cleaner silencer with great simplicity to provide necessary resonance, inertance, acoustical capacitance, and impedance factors necessary to attenuate sound waves otherwise most disturbing.

The chamber 66 formed within walls 42 is a resonator chamber of increased acoustical capacitance due to the greater volume by having walls 42 of greater circumferential dimension than would result in providing a straight cylindrical wall or sleeve between flange 58 of the silencer cover 51 and the wall 16 of the cleaner element. The greatest acoustical impedance obtainable within the limited space available is provided by extending outlet tube 49 within cover 51 and by providing the extension member 47 on the atmospheric side of the acoustical capacitance. The extension member is flared at its inlet end to provide less resistance to air flow through the tube 49. The extension member 47 also provides a longer sound path through the tube 49 within the chamber 41 on the atmospheric side thereby providing greater impedance for attenuating sounds on the atmospheric side where they may be heard. An inertance factor may be broadly said to be provided by the disposition of the outlet end of the tube 49 within cover 51 and close to the walls 52 and 53 thereof. The wall 52 and the flange 58 of wall 53 in combination with the outer surface of the tube 49 provide an annulus of some length and capacity which induces inertance. The apertures 65 formed in tube 49 provide for the more rapid expansion of gases flowing through the tube and are tuned with chamber 66 to eliminate high frequency sounds.

The inertance and resonator characteristics are not provided to attenuate all sounds of low frequency noises but are sufficient in combination with the acoustical capacitance and impedance to have an effect upon low frequency sounds. In addition, such factors are provided with no appreciable increase of material, labor, or rearrangement of structural elements.

The major asset of the proposed cleaner silencer is the provision of a simple acoustical capacitance sufficient, within the space provided, as dictated by its use here with automotive engines, to obtain sufficient sound attenuation. Ordinarily a capacitance coupled to the sound path, here through cover 51 and tube 49, does not remove low frequency noises to a satisfactory level. However, where higher frequency noises are more objectionable a more satisfactory reduction of noise over a desired range is obtained in the use of a simple acoustical capacitance as here provided in conjunction with the other features described.

We claim:

1. A cleaner silencer unit comprising a cleaner element and a silencer element having a common wall and including an elongated conduit having opposite ends extending through said common wall and substantially within said cleaner and within said silencer, a cover member closing said silencer element, the outlet end of said conduit being disposed within said cover member, chamber means formed within said silencer by the walls of said silencer and cover member about said conduit to provide a resonator of predetermined acoustical capacitance for attenuating sounds of high frequency within said cleaner silencer unit, and a plurality of apertures formed through the end of said conduit for communication with said chamber means.

2. The cleaner silencer unit of claim 1 including an extension member secured to the inlet end of said conduit within said cleaner unit for increasing the sound path through said conduit to provide greater acoustical impedance on the atmospheric side of said chamber means.

3. A cleaner silencer unit including a cleaner element and a silencer element formed with a common separating wall, a tubular member having opposite ends extended through said common wall and substantially within said cleaner and said silencer elements to provide communica-

tion therebetween, chamber means formed by the walls of said silencer element about the outlet end of said tubular member, air collecting means provided about the inlet end of said tubular member within said cleaner element, said chamber means providing an acoustical capacitance for attenuating sounds of high frequency within said silencer element, said tubular member extending into said air collecting means sufficiently to provide increased acoustical impedance with said tubular member on the atmospheric side of said silencer unit to assist in the attenuation of sounds otherwise audible within said cleaner element.

4. A cleaner silencer unit including cleaner and silencer elements having a common separating wall therebetween, a tubular member extended obliquely through said common wall within both said cleaner and said silencer elements, an acoustical chamber formed by the walls of said silencer element about the outlet end of said tubular member within said silencer element, a plurality of spaced apertures formed through said tubular member near the outlet end thereof for communication with said acoustical chamber, and an extension member connected to the end of said tubular member within said cleaner element to provide increased acoustical impedance to attenuate sounds within said cleaner silencer unit.

5. A cleaner silencer unit including cleaner and silencer elements having a common separating wall, a tubular member extended obliquely through said wall within both said cleaner and silencer elements for communication therebetween, a cover member closing off said silencer unit and including an outlet opening formed therein communicating with the outlet end of said tubular member, said outlet end of said tubular member being disposed in close spaced relation to the walls forming said cover to introduce an inertance thereabout, a resonator chamber of predetermined acoustical capacitance formed by the walls of said silencer element and cover member about the outlet end of said tubular member, and spaced apertures formed through said tubular member near the outlet end thereof for communication with said resonator chamber, the inlet end of said tubular member extended within said cleaner element providing acoustical impedance sufficient to attenuate sounds not attenuated within said resonator chamber.

6. A cleaner silencer unit comprising a cleaner element and a silencer element having a common separating wall, said silencer element including chamber means formed by the walls thereof, said cleaner element including an air collecting chamber formed by the walls thereof within said chamber means of said silencer element, a conduit extended through said common wall within said chamber means and said air collecting chamber, a cover member secured over said silencer element and having an outlet passage formed therein in communication with

the end of said conduit within said silencer element, a plurality of spaced apertures formed through said conduit near the outlet end thereof for communication with said chamber means, said chamber means providing a resonator chamber of predetermined acoustical capacitance for attenuating sounds of high frequency within said silencer, and said conduit extended within said air collecting chamber of said cleaner element providing acoustical impedance sufficient to attenuate audible sounds on the atmospheric side of said silencer within said cleaner element.

7. A cleaner silencer unit including a casing having cleaner and silencer elements formed therein, a common dividing wall formed within said casing for separating said elements, said dividing wall having an opening formed therein to provide communication between said elements, a tubular member secured within said opening and extending through said silencer element, a cover member secured over said silencer and including an outlet passage, a silencer chamber formed about said tubular member by the walls of said cover and said silencer element, the outlet end of said tubular member extending within the outlet passage of said cover member in close spaced relation to the walls thereof, and apertures formed through said tubular member for communication with said silencer chamber, said silencer chamber having a predetermined acoustical capacitance to provide a tuned resonator for attenuating high frequency sounds within said silencer.

8. A cleaner silencer unit including integrally formed cleaner and silencer elements having a common dividing wall, a cover element secured over said silencer element and including an elongated outlet passage, an opening formed through said dividing wall, a conduit secured within said opening and extended through said silencer element to within close spaced relation of the walls of said cover element forming said outlet passage, a silencer chamber formed by the walls of said silencer and cover elements about said conduit, a plurality of spaced apertures formed through said conduit to provide communication with said silencer chamber for the attenuation of sounds transmitted through said conduit, and said silencer chamber communicating with said outlet passage about the outer end of said conduit between said conduit and said cover walls to provide an acoustical inertance likewise for the attenuation of disagreeable sounds.
